YARN TENSIONING AND SEVERING MECHANISM FOR CIRCULAR KNITTING MACHINES

Vaughn H. Butler, Harriman, Tenn., and Aaron Burleson, Burlington, N.C., assignors, by mesne assignments, to The Gordon Company, Winston-Salem, N.C., a partnership

Filed Dec. 6, 1956, Ser. No. 626,691
4 Claims. (Cl. 66—140)

This invention relates to circular knitting machines, and in particular to improved means and methods for handling and severing yarns on the dial caps thereof.

In the knitting of tubular articles such as seamless hosiery, frequent yarn changes are commonly effected in the course of the knitting cycle. In the case of hosiery, for example, the welt and leg may be knitted of different yarns, and heavier yarns are frequently employed in the heel and toe. At each yarn change an inactive yarn is dropped into the needles for knitting and an active yarn is withdrawn from the knitting a few needles later. Two yarns extend from the resultant yarn lap, and these are commonly severed so as to be an inch or two in length. Since yarn ends of such length are easily noticeable and unsightly, they must be clipped, and this is usually done individually and manually during inspection. The yarn ends are clipped down to a length of $\frac{1}{4}$ " or $\frac{3}{8}$ ", which is commercially satisfactory. The clipping operation is obviously time consuming and expensive, and exposes the stockings to possibility of damage.

A principal object of the present invention is the provision of novel means and methods for holding and tensioning yarns over the dial cap of the machine by means of suction, whereby better and more reliable control of the yarns is effected.

The yarns so tensioned may be automatically severed close to the fabric during yarn changes, with such reliability as to eliminate subsequent inspection and clipping of free ends. Additionally, the improved mode of tensioning assures positive yarn laps, principally by effectively holding and tensioning inactive yarns prior to and during insertion into the fabric. Related objects are to provide means and methods for positively picking up and removing cut ends severed from newly inserted yarns, and to pick up and engage the ends of newly withdrawn yarns, and hold them in readiness for reinsertion.

A particular object of the invention is the provision of a novel combination suction and clamping device for circular knitting machines, adapted to facilitate automatic severing of newly inserted yarns close to the fabric being knitted.

Another object of the invention is to provide novel yarn severing means and methods for circular knitting machines, involving the use of a resistance wire heated to red heat prior to and during yarn changes and adapted to sever yarns on contact by the local application of intense heat thereto, close to the fabric being knitted. Further objects will be in part evident and in part pointed out hereinafter.

The invention and the novel features thereof may best be made clear from the following description and the accompanying drawings in which:

FIGURE 1 is a side elevational view of a preferred embodiment of the invention, illustrating a combination suction and clamping device in operative association with related parts of the knitting machine;

FIGURE 2 is a vertical sectional view through the yarn tensioning mechanism of FIGURE 1;

FIGURE 3 is a view taken on the line 3—3 of FIGURE 2;

FIGURE 4 is a view taken on the line 4—4 of FIGURE 2;

FIGURE 9 is a plan view illustrating the operation of the FIGURE 8 embodiment during yarn insertion;

FIGURE 10 is a similar view illustrating the operation of the FIGURE 8 embodiment during yarn withdrawal, and

FIGURE 11 is an elevational view of the pneumatic system of the invention.

Referring to the drawings in detail, FIGURE 1 illustrates a portion of a conventional seamless hosiery machine, such as a 400 needle Model KN Scott & Williams machine. As shown, the latch ring 20 encloses the knitting station indicated generally as 22, the latter being provided with a yarn guide plate 24 and a plurality of yarn fingers 26 which are individually retractable and function as interchangeable yarn feeds. The yarn fingers are pivotally mounted at 28, and actuated in conventional manner by thrust bars maintained in contact with the main pattern drum of the machine. Knitting yarns 30 pass through eyes in the guide plate 24 and through the ends 32 of the yarn fingers 26, the active yarn extending from its yarn finger to the adjacent knitting needles 32. The needles 32 are independently mounted in the rotating cylinder of the machine, and extend thereabove adjacent the periphery of the dial and dial cap 34. The usual dial drive pinion 36 is mounted on the upper end of dial drive shaft 38 (FIGURE 5), which serves to effect rotation of the transfer jacks 40 in synchronism with the cylinder.

On the dial cap, slightly beyond the position of the yarn fingers in the direction of cylinder rotation (counterclockwise in FIGURE 5), is mounted a guide tongue 42. Therebeyond, at a position spaced angularly from the knitting station 22 by about 90°, the conventional clamp and shear mechanism of the dial cap is replaced in accordance with the present invention with a novel yarn tensioning device indicated generally as 44. As best shown in FIGURE 2, the tensioning device 44 comprises a block or housing 46 mounted a short distance, such as $\frac{1}{16}$ " or $\frac{1}{8}$ ", above the dial cap, as by means of screws 48 engaging and extending through the housing and into the dial cap. As best shown in FIGURE 2, a bore 50 extends vertically through the housing 46, the bore having a sleeve 52 slidably mounted therein. The sleeve 52 is closed at its upper end 54 to define an internal chamber 56, and extends upwardly beyond the housing as a solid rod portion 58. The sleeve 52 is provided with diametrically opposed vertically extended slots 60 and 62 opening into the internal chamber thereof. A pressure conduit 64 extends through the housing 46, being secured in place as by screw 66, and is formed into a nozzle end 68 extending through the sleeve slot 60 and terminating a short distance inwardly thereof. An exhaust conduit 70 extends through the housing and into the opposite sleeve slot 62, the exhaust conduit being suitably retained in place as by the bracket 72 extending therefrom to a position over the top of the housing, where it is anchored by screw 74. As will be understood, limited movement of the sleeve 52 in vertical direction relative to the housing 46 and conduits 64 and 70 is permitted by the extended slots 60 and 62. A vertical slot 76 in the upper end of rod portion 58

encloses an end of lever 78, these elements being pivotally engaged by a pin 80 extending therethrough. The lever 78 is pivoted approximately at its center 82, and the opposite end thereof is engaged by an actuating rod 84, which extends upwardly through a bore in the extension 86 carried on the end of the operating lever 88. The actuating rod 84 is flexibly engaged to the operating lever extension 86 by its lock collars 90 and spring 92, whereby vertical movement of the operating lever acting through lever 78 serves to move the sleeve 52 into and out of contact with the dial cap 34, the spring 92 accommodating over travel of the operating lever. The operating lever 88 is actuated in conventional manner by a thrust rod maintained in engagement with a cam on the main drum, and may conveniently be the standard operating lever provided to operate the usual clamp and shear mechanism.

Beyond the yarn tensioning device 44, and angularly spaced therefrom in the direction of cylinder rotation approximately 90°, a novel yarn severing means 100 may be mounted on the dial cap. As shown in FIGURES 1 and 5, the yarn severing means comprises an insulating block 102 provided with side sockets 104. A short length of electrical resistance wire 106, which may be nickel-chromium alloy, platinum or the like, extends between the sockets 104, being retained therein in firm electrical contact by set screws 108. The resistance wire 106 is formed into a generally vertically extending leading section 110 disposed closely adjacent the path of the needles 32, preferably about $\frac{1}{16}$ " therefrom, and the upper surface of the dial cap adjacent the severing means is formed into a guide channel 112 adapted to direct yarns sliding over the dial cap into contact with the wire leading section 110. Connector posts 114 are provided on the inner end of the insulating block 102 for the attachment of electrical conductors 116, the connector posts being electrically connected through the block 102 to the sockets 104, as will be understood.

As shown in FIGURE 7, current is supplied to the conductors 116 and resistance wire 106 by a transformer 118. The transformer 118 is powered by a source 120 through a switch 122, preferably of the Micro switch type. A centrifugal switch 124 may be provided in series with the switch 122, this switch being engaged, as by its gear 126, to any convenient element of the machine which moves constantly while the machine is in operation. The centrifugal switch, for example, may be dryingly engaged to the segment drive gear 128, and a manually operated switch 130 bypassing the centrifugal switch may be provided for testing purposes.

The switch 122 is conveniently mounted as by bracket 132 on a frame element 134 of the machine, and is normally maintained open by downward pressure of an arm 136 fixed to the upper end of the conventional stop motion actuating rod 138 of the machine. The stop motion actuating rod is vertically displaced, as is well known, by a link 140 extending from the pawl 142, which is disposed over the chain ratchet and the machine chain 144. The chain 144 is provided at intervals with lugs 145 adapted to elevate the pawl 142, and for a purpose presently apparent each chain link 148 preceding each chain lug 146 which corresponds to a yarn change is provided with a low cam 150, adapted to elevate the pawl 142, actuating rod 138 and arm 136 of the latter very slightly, sufficient merely to permit switch 122 to close.

The invention also comprises a pneumatic system, which is illustrated in FIGURE 11. As there shown, a pressure air line 160 leads to an air valve 162 suitably mounted on the machine. The valve outlet discharges into a small reservoir 164, which in turn communicates with a pressure line such as flexible hose 166 connected to the pressure conduit 64 of the yarn tensioning device 44. An actuating link 168 is pivotally mounted at 170, and disposed adjacent and in alignment with the valve stem 172 of valve 162. The outer end of link 168 is

connected by rod 174 to a bell crank 176, pivoted at 178 and maintained by the action of spring 180 in contact with a ring cam 182 mounted on the main drum of the machine. A second valve operating link 184 may be pivotally mounted alongside link 168 to facilitate manual operation of the valve 162.

Function and operation of the invention will now be described in connection with FIGURES 1, 5, 6, 7 and 11. Referring initially to FIGURE 5, it may be assumed that the machine is operating in normal round-and-round knitting, as would be the case in knitting a stocking welt. The yarn finger 26A is illustrated in active position, feeding yarn 30A into the needles 32 for knitting. The yarn finger 26B, in common with the other yarn fingers illustrated, is up in inactive position, and the yarn 30B extends therefrom under guide tongue 42, into the open bottom end of sleeve 52 of the tensioning device 44, and into the exhaust conduit 70 thereof.

Referring next to FIGURE 7, the pawl 142 is during straight knitting in lowermost position, as are also link 140 and the stop motion actuating rod 138, whereby the arm 136 engages the switch 122 and maintains this switch open, so that no current passes to the transformer 118 and the resistance wire 106 of the yarn severing means 100. The machine being in operation, it may be noted that the segment drive gear 128 is rotating, thereby rotating the centrifugal switch 124 and maintaining this switch closed.

While straight knitting of the yarn 30A proceeds, the bell crank 176 rides a high portion of the ring cam 182 (see FIGURE 11), thereby disposing the actuating link 168 in the position illustrated, out of contact with the stem 172 of the air valve 162, whereby the valve is in normally closed position. The operating lever 88 (FIGURE 1) and the associated actuating rod 84 are in down position, so that the lever 78 maintains the sleeve 52 in elevated position as permitted by its slots 60 and 62. In such elevated position, the lower edge of sleeve 52 is substantially at the level of the lower surface of housing 46, or about $\frac{1}{16}$ " to $\frac{1}{8}$ " above the dial cap. This represents the relationship of the parts while straight knitting proceeds.

As the machine approaches a yarn change, a chain lug 146 corresponding to the yarn change approaches the pawl 142. The preceding low cam 150 passes under the pawl 142, lifting the pawl, the rod 138 and its arm 136 sufficiently to permit switch 122 to close. This permits a low voltage, for example two volts, high amperage current to flow through the resistance wire 106, which immediately begins to heat up. Since it is desired that the resistance wire be at red heat during the yarn change, the low cam 150 provides the required preliminary heat up time. If necessary, two or more chain links 148 preceding each chain lug 146 corresponding to a yarn change may be provided with low cams 150, to provide adequate heat up time. As will be evident, should the machine be stopped while the switch 122 is closed by a cam 150 or a lug 146, the centrifugal switch 124 will come to rest and open, thereby cutting off the current flow through resistance wire 106.

As the machine goes into the yarn change, a jog of the main drum permits the bell crank 176 (FIGURE 11) to drop into a low portion of the associated ring cam 182. The spring 180 rotates the bell crank the permitted distance, and through rod 174 rotates the actuating link 168 into contact with stem 172 of valve 162, and displaces the valve stem inwardly to open the air valve. High pressure air immediately flows into reservoir 164 and through flexible hose 166 into the pressure conduit 64 of the tensioning device 44. The high pressure air flow enters the chamber 56 of sleeve 52 through nozzle end 68, which is directed at the opposite open end of exhaust conduit 70. As will be understood, the pressure conduit 64, sleeve chamber 56 and exhaust conduit 70 together constitute a continuous air path or conduit for the air

flow. The high velocity air flow through the chamber 56 effects an aspirating action, creating a suction in the chamber 56 and causing air flow into the open bottom end thereof. The free end of the inactive yarn 30B is engaged by this air flow into the chamber 56, and by the high velocity flow into the exhaust conduit 70, and thereby drawn taut against the restraining influence of guide tongue 42, yarn finger 26B, guide plate 24, and the conventional yarn tensioning and feeding elements of the machine, and effectively tensioned.

Substantially simultaneously, the yarn finger 26B is dropped to active position, whereby the yarn 30B passes between the needles 32 and is taken thereby. The positive and effective tensioning of the inactive yarn as it is dropped into the knitting, it is found, assures that the inactive yarn is taken by the needles at the desired point, thereby assuring positive yarn laps.

Referring to FIGURE 5, the newly inserted yarn is carried by the first needle to knit in counterclockwise direction. The first needle to knit is indicated as 32', and initially carries the yarn 30B to the position illustrated as 30B'. In movement from initial knitting position to the position 30B', the free end of the newly activated yarn is partially drawn out from under the guide tongue 42. As the distance from the needle 32' to the sleeve 52 decreases, the free end of the yarn 30B is drawn up into the sleeve 52 and into the exhaust conduit 70 of the yarn tensioning device by air movement, whereby the slack is taken up and tension on the free end is preserved.

As the first needle to knit 32' reaches a position adjacent the yarn tensioning device, the free yarn end assumes the position 30B'', the tensioning device functioning as previously described to take up the slack therein and maintain effective tension on the yarn end. At this moment, preferably, the operating lever 88 is elevated by drum movement, elevating the actuating rod 84 to rotate the lever 78 and move the sleeve 52 downwardly into contact with the dial cap, that is to the relative position illustrated in FIGURE 2, whereby the yarn 30B is firmly clamped between the lower edge of the sleeve 52 and the upper surface of the dial cap. As the yarn is carried by the first needle to knit 32' successively to the positions 30B''' and 30B'''' of FIGURE 5, as will be understood, the needle 32' must draw the free yarn end out from under the sleeve 52, against the restraining influence of air movement in the chamber 56 and into exhaust conduit 70, and also against the frictional engagement of the yarn between the sleeve and the dial cap. In this manner, the free yarn end is controlled and highly tensioned in positive manner during this portion of the yarn change cycle.

When the tensioned yarn end is carried by the needle 32' to the position 30B'''', it is carried into contact with the leading section 110 of resistance wire 106, the dial cap guide channel 112 assuring the desired alignment. The resistance wire 106 is by this time at red heat, approximately 1,500° F., and the yarn end is severed on contact by the local application of intense heat thereto. The resistance wire severs yarns of nylon, cotton and other fibers with equal facility and reliability, and due to its positional relationship and to the positive control of the travelling yarn invariably severs the yarn within about $\frac{1}{4}$ inch of the fabric.

After the needle 32' passes the yarn severing means 100, the operative lug 146 passes from under the pawl 142, permitting the pawl 142 and the associated stop motion actuating rod 138 to drop, whereby the rod arm 136 engages and opens the switch 122. This cuts off the current from the resistance wire 106, which then cools and remains cool until immediately prior to the next yarn change. Substantially simultaneously, the operating lever 88 is caused to drop, rocking the lever 78 and elevating the sleeve 52 to its up position, releasing the severed yarn end from frictional engagement.

Also, the bell crank 176 is pivoted by movement of

ring cam 182, and displaced to the relative relationship illustrated in FIGURE 11. This movement of the bell crank 176 displaces the actuating link 168 out of contact with the stem of air valve 162, and permits the valve to close. The pressure air in reservoir 164 maintains pressure air flow through the flexible hose 166 and the yarn tensioning device for a brief interval of time after the valve 162 is closed. This assures temporary maintenance of suction in the chamber 56 and air flow through the exhaust conduit 70 of the yarn tensioning device, which is effective to remove the severed end of the yarn 30B through the exhaust conduit 70 of the tensioning device. A screen receptacle may be provided on the far end of the exhaust conduit 70, to retain these severed ends.

The foregoing describes the operation in connection with the newly inserted yarn 30B. Substantially concurrently, as will be understood, the yarn 30A is removed from active knitting. The active yarn finger 26A is elevated to inactive position a brief interval of time after the yarn finger 26B is dropped into knitting position, this interval of time corresponding to the passage of, for example, eight needles. Referring to FIGURE 6, it will be seen that the yarn 30A is carried by the last needle 32'' to take the yarn away from the yarn finger 26A, being drawn by the needle 32'' through the yarn finger and the conventional yarn feeding and tensioning means of the machine. The yarn is drawn initially after withdrawal to the position 30A', at which position it begins to pass under the guide tongue 42. As the last needle to knit 32'' proceeds around the dial cap, the yarn is extended to the position 30A'' illustrated, at which position it engages the outside surface of the sleeve 52, then in down position, and wraps around the sleeve or perhaps is drawn thereunder to some degree. The yarn 30A is subsequently extended to the illustrated position 30A''', in which position it is drawn into contact with the leading section 110 of the resistance wire 106, and severed close to the fabric in the manner described in connection with the newly inserted yarn. In the case of the yarn 30A being withdrawn from the knitting, the suction and frictional effect of the yarn tensioning device thereon appear to be minor, but it has been found that the yarn is invariably effectively tensioned by the yarn feeding device, and the combined resistance of its yarn finger, the guide tongue 42 and the yarn tensioning device 44. The opening of the circuit to the resistance wire 106 may be timed to coincide with the arrival of the yarn being withdrawn thereat, or to occur shortly thereafter. Upon the elevation of the sleeve 52, as previously described, the severed end of yarn 30A is sucked up into the chamber 56 and into exhaust conduit 70, the delayed termination of air movement assuring this, and the yarn end is thereby engaged by the yarn tensioning device and retained for subsequent reinsertion. That is, at the end of the yarn change, the end of the withdrawn yarn assumes the position formerly held by the newly inserted yarn, prior to the yarn change. As will be evident, the operation of the device is not limited to two yarns, but three or four or more yarns may be handled with equal facility.

A simplified embodiment of the invention, which utilizes suction effect as the sole means of holding and tensioning the yarns over the dial cap, is illustrated in FIGURE 8. In this embodiment, the yarn tensioning device indicated generally as 190 is disposed at the position of the yarn tensioning device 44 described in connection with the previous embodiment. The yarn tensioning device 190 comprises a conduit 192, which may be a short length of copper tubing, having a side branch 194 extending therefrom, the side branch opening a short distance, perhaps $\frac{1}{16}$ or $\frac{1}{8}$ inch, above the dial cap at a point angularly spaced approximately 90° from the knitting station in the direction of cylinder rotation, and situated adjacent the periphery of the dial cap. The conduit 192 and its side branch 194 may be suitably mounted and positioned by means of a bracket 196, mounted on and extending

from the bearing bracket 193 of the machine. The flexible air pressure hose 166 is joined to the inlet end of the conduit 192, as shown, and adjacent the juncture of branch 194, a nozzle 200 is formed in the conduit 192, this nozzle terminating adjacent the juncture of the branch and being directed toward the outlet end of the conduit 192. As will be understood, when a high velocity air stream is passed through the conduit 192 from the inlet to the outlet end thereof, the nozzle 200 and side branch 194 function as an aspirator, causing a suction in the branch 194 and inducing an air flow into the open end thereof.

The yarn severing means 100 of the previously described embodiment may be utilized without change, and the pneumatic system may be in all respects as previously described. In this embodiment, however, the actuating rod 84 of the machine is not utilized and the lever 78 and associated elements are omitted.

Function and operation of the FIGURE 8 embodiment will be described in connection with FIGURES 9 and 10. Prior to a yarn change, one yarn finger such as 26C is down in active position, feeding its yarn 30C directly into the needles 32. The inactive yarn fingers 26D and 26E are in up position, and yarns extend therefrom (see FIGURE 8) under guide tongue 42, into the open lower end of side branch 194, and into the outlet portion of the conduit 192. Immediately prior to the yarn change, the resistance wire 106 is heated as previously described. Next, or substantially simultaneously, a jog of the main drum effects rotation of bell crank 176 (FIGURE 11), and actuating link 168 is displaced to open the air valve 162. High pressure air thereupon flows through reservoir 164, flexible hose 166, and conduit 192 of the yarn tensioning device. The air flow through the conduit 192, as previously indicated, creates a vacuum in the side branch 194 and effects a high velocity air flow through the outlet end of the conduit 192, which combine to exert effective tension on the free ends of the inactive yarns 30D and 30E.

Assuming the yarn 30C is to be replaced in the knitting by the yarn 30D, substantially simultaneously the yarn finger 26D is dropped to active position, whereupon its yarn is engaged by the needles 32 and drawn into the knitting. The tension exerted by the tensioning device 190 on the inactive yarn insures that it is taken by the intended needles, and that a positive yarn lap results. Referring to FIGURE 9, the newly inserted yarn 30D is carried by the first needle to knit initially to the position 30D', at which point the yarn is drawn partially out from under the guide tongue 42. Air movement through the conduit 192 takes up the slack in the yarn end, and maintains effective tension thereon.

The yarn end is carried subsequently by the first needle to knit to the position 30D", at which time the first needle to knit the newly inserted yarn passes closely adjacent the side branch 194, and the air movement through the conduit 192 functions as previously described to take up the slack in the free yarn end and maintain effective tensioning thereof. Subsequently the end of the newly inserted yarn is carried by the first needle to knit to the position 30D''. In the course of movement from the position 30D'' to the position 30D''', the yarn end is extended with respect to the side branch 194, and drawn out therefrom, against the restraining influence of the air flow. These factors combine to maintain effective tension on the yarn end as it is guided by the guide channel 112 into contact with the leading section 110 of the resistance wire 106, as that severing of the yarn by the resistance wire 106 close to the fabric is insured. As in the previous embodiment, the yarn tensioning device 190 is effective to manipulate and tension the yarn for severing within about $\frac{1}{4}$ inch of the fabric. The severed end is carried away through the outlet portion of conduit 192.

A brief interval of time after the yarn 30D has been inserted into the knitting, perhaps 8 or 10 needles later, the

5 formerly active yarn 30C is withdrawn from the knitting by elevation of its yarn finger 26C. Upon withdrawal of the yarn 30C from the knitting, the yarn end is carried by the last needle to knit this yarn initially to the position 30C' (see FIGURE 10) at which position the yarn is drawn under the guide tongue 42. The yarn 30C is carried thereafter by the last needle to knit to the position 30C'', at which position it is well under the guide tongue 42, and extends as well under the end of side branch 194 of the yarn tensioning device. The suction in the side branch 194 and the resultant air flow thereto tend to draw the yarn 30C up into the side branch 194, so that a bight of the yarn extending from the yarn finger to the last needle to knit is drawn up against the lower end of the side branch and into the interior thereof. This engagement of a bight of the yarn length takes up all slack therein, and applies effective tension thereto.

10 The last needle to knit the previously active yarn subsequently carries the yarn to the position 30C''', and into contact with the resistance wire 106. In progressing from the position 30C''' to the position 30C''', the yarn 30C is extended with respect to its yarn finger 26C, but a travelling bight thereof remains engaged in the branch 194 of the tensioning device by the previously described suction effect, whereby the yarn end assumes the angled position illustrated in FIGURE 10, both segments thereof being effectively tensioned by the tensioning device. As the yarn 30C is guided into contact with the leading section 110 of the resistance wire 106, it is severed as previously described, close to the fabric so as to leave an end extending therefrom only about $\frac{1}{4}$ inch long. As soon as the yarn 30C is severed from the fabric, the free end extending from the yarn finger 26C is immediately drawn up into the side branch 194 and the outlet section of the conduit 192, whereby it is engaged and retained for subsequent reinsertion into the knitting. The final disposition of the end of the now inactive yarn 30C is as illustrated in FIGURE 8. As in the previous case, the reservoir 164 of the pneumatic system insures that air flow through the conduit 192 persists until the newly withdrawn yarn has been severed and effectively engaged. It will be recognized that the yarn tensioning device 190 eliminates all moving parts from the dial cap.

15 The bypass switch 130 of the electrical circuit is useful for testing the resistance wire 106, and for other purposes. The resistance wire may be tested when the machine is at rest, by closing the bypass switch, and manually elevating the arm 136 to permit switch 122 to close. It will be evident that chain lugs 146 not corresponding to yarn changes effect minor heating of the resistance wire 106 in passing under the pawl 142. This occasional minor heating is not detrimental, and may be eliminated if desired by incorporation of another switch, operated by a main drum cam, into the electrical circuit.

20 The yarn tensioning device of the invention is particularly effective with the novel yarn severing means disclosed. It will be apparent, however, that the yarn tensioning device may be employed with other means to sever the yarn, such as a high speed reciprocating shear. It will thus be seen that there has been provided by this invention apparatus and methods in which the various objects hereinbefore set forth, together with many practical advantages, are successfully achieved. As various possible embodiments may be made of the several features of the above invention, all without departing from the scope thereof, it is to be understood that all matter hereinbefore set forth or shown in the accompanying drawings is to be interpreted as illustrative, and not in a limiting sense.

25 We claim:

30 1. In a circular knitting machine having a rotary cylinder with independent needles, a dial cap mounted adjacent the top of said cylinder, and a group of individually retractable interchangeable yarn feeds, yarn tensioning means comprising a conduit having an open end disposed above said dial cap at a point angularly spaced from said

yarn feed group in the direction of cylinder rotation, means for inducing air flow into said open end, and means for displacing said open end into and out of clamping relationship with said dial cap.

2. In a circular knitting machine having a rotary cylinder with independent needles, a dial cap mounted adjacent the top of said cylinder, a group of individually retractable interchangeable yarn feeds, and a timing drum controlling the movement of said yarn feeds, yarn tensioning means comprising a conduit having an open end disposed above said dial cap at a point angularly spaced from said yarn feed group in the direction of cylinder rotation, means for inducing air flow into said open end, and means actuated by said drum for displacing said open end into and out of clamping relationship with said dial cap.

3. In a circular knitting machine having a rotary cylinder with independent needles, a dial cap mounted adjacent the top of said cylinder, and a group of individually retractable interchangeable yarn feeds, yarn tensioning means comprising a housing disposed above said dial cap at a point angularly spaced from said yarn feed group, a bore extending vertically through said housing, a sleeve slidably mounted in said bore, the upper end of said

sleeve being closed, said sleeve having diametrically opposed vertically extended slots in the walls thereof, a conduit member extending through said housing and one of said slots into the interior of said sleeve, a second conduit member extending through said housing in alignment with the other of said slots, and means for vertically displacing said sleeve to move its lower end into and out of clamping relationship with said dial.

4. A circular knitting machine as defined in claim 3, including a timing drum controlling the movement of said yarn feeds, said timing drum also actuating said sleeve displacing means.
